COMBINATION FEEDER AND OILER

Daniel C. Cusenbary, Cunningham, Kans.

Application August 9, 1952, Serial No. 20,960

Term of patent 14 years

(Cl. D12—2)

To all whom it may concern:

Be it known that I, Daniel C. Cusenbary, a citizen of the United States, residing at Cunningham, county of Kingman, State of Kansas, have invented a new, original, and ornamental Design for a Combination Feeder and Oiler, of which the following is a specification, reference being had to the accompanying drawing, forming a part hereof.

Fig. 1 is a side elevation of a combination feeder and oiler embodying my new design.

Fig. 2 is a perspective view of the same, the food protecting hood being located 90° with relation to its Fig. 1 position; and

Fig. 3 is an end view of the same with the food protecting hood in the same position as in Fig. 1.

I claim:

The ornamental design for a combination feeder and oiler, as shown.

DANIEL C. CUSENBARY.
